(57) CLAIM

The ornamental design for a bed for animals, as shown and described.

DESCRIPTION

In the drawings, the broken lines depict portions of the bed for animals that form no part of the claimed design.
